UNITED STATES PATENT OFFICE.

GEORGE P. REED, OF MELROSE, MASSACHUSETTS.

WATCH-KEY.

SPECIFICATION forming part of Letters Patent No. 231,729, dated August 31, 1880.

Application filed July 1, 1880. (No model.)

To all whom it may concern:

Be it known that I, GEORGE P. REED, a citizen of the United States, residing at Melrose, in the county of Middlesex and State 5 of Massachusetts, have invented certain new and useful Improvements in Watch-Keys; and I do hereby declare the following to be a full, clear, and exact description of the invention, such as will enable others skilled in the art 10 to which it appertains to make and use the same, reference being had to the accompanying drawings, and to letters or figures of reference marked thereon, which form a part of this specification.

15 This invention relates to means for concealing the winding-pipe of a watch-key by the employment of a sleeve loosely encompassing the barrel or body of the key, and adapted, when the key is suspended from one end, to 20 drop over and conceal the pipe, or be pushed over the same by hand, if necessary, the sleeve being prevented from escape by suitable means, and converting a watch-key into an ornamental appendage for a watch-chain, resembling the 25 lead-pencil now much worn.

The drawings accompanying this specification represent, in Figure 1, a side-elevation, and in Fig. 2 a longitudinal section, of a watch-key containing my improvements.

30 In these drawings, the body or barrel of the key is shown at A as a straight rod or tube, one half of which is of larger diameter than the other, as shown at B, to form a shoulder, a, at the middle of the key, or thereabout, the 35 end of the larger portion A terminating in the winding-pipe b, common to watch-keys.

C represents a sleeve composed of a straight tube of a diameter to loosely encompass the larger half B of the key, and after being 40 passed over such portion B is turned down at its inner end over the shoulder a, as shown in Fig. 2 of the drawings, by which an annular lip, c, is formed, which engages the shoulder and prevents escape of the sleeve in the direction of the pipe b, and yet permits of end 45 play of the sleeve upon or about the smaller or upper half, d, of the barrel A.

To prevent escape of the sleeve in the opposite direction, its lower or outer end is contracted to a diameter less than that of the lower portion, B, of the barrel, as shown at e.

To expose the pipe b preparatory to winding a watch, the sleeve C is pushed inward until the pipe is uncovered, and as the key would 55 be naturally held in a horizontal position while

the winding of the watch takes place, the sleeve would not interfere with the operation, or if it should drop into contact with the cover of the watch-case would do no harm.

When the watch is wound and the key is 60 permitted to hang from the chain the sleeve will drop over the pipe and conceal it, or if sufficient friction existed between the two to prevent this the sleeve may be pushed by hand over the pipe. 65

Objection exists with many persons to wearing a watch-key (when it is known as such) upon a watch-chain. By the employment of the sleeve C the real character of the key is disguised, and it cannot be detected from the 70 ornamental lead-pencil now so common, in which one portion slides upon another with a telescopic joint.

The swivel in the upper end or head of the barrel A, to which allusion has before been 75 made, is shown as composed of a spherical ball, f, let into a socket, g, in the end of the barrel, and with the edge of the socket turned over upon and so as to inclose the largest diameter of the ball, by which means escape of the latter is prevented, and it is permitted universal 80 freedom of motion.

The ring by which the key is suspended is shown at h as passed through the outer side of the ball f, which completes the key. 85

I do not confine myself to the form of the ball f as represented in a true sphere, as in place of this a cylindrical disk of other shapes may be used—as, for instance, a flattened ellipsoid, a truncated cone, &c.—and effect a 90 substantially like result so long as its greater diameter was inclosed in the socket.

I claim—

1. In combination with a cylindrical case, a watch-key provided with a barrel or shank 95 that protrudes through the rear end of said case.

2. In combination with case C, open only at the ends, a key consisting of protruding barrel A, enlargement B, and winding-pipe b, 100 substantially as set forth.

3. In combination with cylindrical case C and key A B b, a ring, h, attached to said key by a ball-and-socket joint.

In testimony whereof I affix my signature 105 in presence of two witnesses.

GEORGE P. REED.
